GAUGE COCK

William E. Whaley, Overton, Tex., assignor to
Alva G. Blanchard, Shreveport, La.

Application July 22, 1936, Serial No. 92,053

2 Claims. (Cl. 251—126)

This invention relates to new and useful improvements in gauge cocks and particularly to high pressure boiler gauge cocks.

One object of the invention is to provide an improved gauge cock having a large seating capacity together with means for effecting a quick and easy change from an old seat to a new seat.

An important object of the invention is to provide means for releasing the seating member for shifting, prior to the unseating of the gauge nozzle, whereby said nozzle need remain unseated only momentarily during the shifting of the seating member.

Another object of the invention is to provide a gauge cock having means whereby the nozzle will repeatedly engage the seating surface at the same point of contact until shifted out of alignment with each other thereby enabling a seat to be used several times with positive and effective results.

A further object of the invention is to provide a gauge cock having means for deflecting fluid, emitting from the nozzle, away from the handle and the movable parts of said gauge, whereby the hands of the operator are protected from said emitting fluid, and the danger of corroding or sticking of said movable parts is minimized.

A still further object of the invention is to provide a reversible seating member which may be easily and conveniently reversed to provide additional seating surface, together with the seating member being of such composition and construction as to enable the seating surface thereof to be renewed by hammering or the like.

Another object of the invention is to provide means for contacting the seating member and the nozzle under increased pressure without increasing the weight of said gauge cock, whereby a positive and effective seat is assured.

Another object of the invention is to provide a design of gauge cocks economical to manufacture and easy to assemble.

A construction designed to carry out the invention will be hereinafter described together with other features of the invention.

The invention will be more readily understood from a reading of the following specification and by reference to the accompanying drawing in which an example of the invention is shown, and wherein:

Figure 1 is a plan view of a device constructed in accordance with the invention.

Figure 2 is an elevation of the same.

Figure 3 is a vertical sectional view taken on line 3—3 of Figure 1.

Figure 4 is a transverse vertical sectional view taken on line 4—4 of Figure 2, and

Figure 5 is a perspective view showing the device in an open position.

In the drawing the numeral 10 designates a nipple having a screw-thread shank, 11, at one end and its other end terminating in a reduced conical shaped nozzle 12. A flat portion, 13, is provided intermediate the ends as a suitable wrench hold for convenience in installation. An axial bore, 14, extends inwardly from the nozzle 12 midway of said nipple, with the inner end of said bore opening into an enlarged axial bore 14', 15, of the shank 11. The outer end of the bore 14 is flared to provide a bevelled tip 12' on the nozzle 12.

A bracket 15, integral with the nipple, overhangs the nozzle and is provided in its outer end with an aperture 16 for receiving a screw-threaded bolt 17. This bolt likewise extends through apertures 18' and 19' respectively in upturned ears 18 and 19 of a spring collar or clamp 20, thereby pivotally connecting the collar and 25 the bracket. The aperture 18' (Fig. 4) may be of angular shape for receiving an angular portion 21 of the bolt 17 whereby the same may be held against rotation. A wing nut 22 provided on the bolt makes for convenience in tightening 30 or loosening the tension of the collar about a circular head 23, which is supported in said collar.

The collar is positioned upon a flanged bushing 24, which is preferably of some non-corrosive 35 material such as brass, and which is assembled upon the head with a tight fit against the angular shoulder on the circular head 23. An elongated shank 25 extending from the outer end of the head constitutes a weighted handle while 40 upon the inner end of the head is provided a tapped hold 26' adapted to receive a cap screw 26 which holds in place circular discs 27' and 27. Disc 27' holds spring collar 20 properly assembled upon the flanged bushing 24 and upon the head 45 23. Disc 27 is a seating member and is of a soft metal such as a composition of lead and babbitt, so that when said member is engaged under pressure with the nozzle tip 12' an indented seat is readily formed in the surface of the member, 50 thereby effectively closing and sealing the nozzle. It will be noted that the nozzle engages the seating member in close proximity to the pivotal bolt 17, whereby the maximum pressure caused by the weight of the head 23 and the handle 25 will 55

be exerted to hold the member in engagement with the nozzle.

The bolt 17 has a close sliding fit with the apertures 16, 18' and 19' of the bracket 15 and the ears 18 and 19, whereby the collar and likewise the member 27 is held in true alignment with the nozzle. Such alignment will cause the nozzle to engage the same seat indentation until the member is shifted, thereby enabling a seat to be used several times with effective results.

10 The wing nut 22 provides a convenient adjustment for readily loosening the collar so that the head 23 and likewise the member 27 may be rotated to position a new seat opposite the nozzle. Approximately 40 seat indentations may be had on each side of the member and when all available seats on one side have been used said member may be removed and reversed by removal of cap screw 26.

20 The seating surfaces of the member may be removed by hammering them until a sufficiently smooth surface is presented, thus permitting said member to be used over and over again until completely worn out or it is desired to replace it.

25 It is pointed out that the outer portion of the member 27 extends beyond the head, thereby forming an annular protuding flange which serves to deflect any fluid, such as steam or hot water, emitting from the nozzle when the gauge cock is in an open position, as shown in Fig. 5. This deflection of the emitting fluid protects the movable parts of the gauge cock from such fluid and minimizes the danger of said movable parts corroding or sticking. Likewise, the hands of 30 the operator are safeguarded against burns and scalding.

The various parts of the gauge cock may be made of any suitable material, and favorable results have been obtained with a nipple made of a composition of copper and bronze, and with the head and handle of a malleable iron casting. It is preferable that the collar 20 be made of non-corrosive spring steel, and the bolt 17 and wing nut 22 and bushing 24 also be made of a 40

non-corrosive metal, thus assuring the expansion of the collar when the wing nut is loosened, as well as the operativeness of the gauge at all times.

It is pointed out that the wing nut provides a singular adjustment whereby the seating member may be freed for shifting, which together with the reversibility of said seating member and its resultant large seating capacity assures a gauge cock of convenient operation and having 10 a long and efficient life of usefulness.

Furthermore, the engagement of the nozzle 12 with the upper portion of the seating member and in close relation to the pivotal mounting of the collar effects a seating contact under the 15 maximum pressure obtainable from the weight of the head 23 and handle 25, whereby a positive and effective seat is assured.

Various changes in the size and shape of the different parts, as well as modifications and alterations, may be made within the scope of the 20 appended claims.

What I claim is:

1. In a gauge cock, a nipple having an axial passage, a supporting arm on said nipple projecting forwardly above said nipple, a circular head, a circular support hinged to said arm and fitting about said head and in which said head is rotatable, a soft metal disc fixed on said head facing said nipple, a handle projecting forwardly 25 from said head by means of which said head and disc may be adjusted in said support, the axis of said head and disc being below the axis of said nipple.
2. In a gauge cock, a fluid discharging nipple, 35 an arm extending from said nipple, a handle, a seat facing thereon presented toward said nipple, a ring hinged to said arm and swivelly supporting said handle which may be rotatably adjusted in said ring, whereby new surfaces on said 40 seat facing may be presented to said nipple by rotating said handle in said ring.

WILLIAM E. WHALEY.
